TRAVELING SCAFFOLD

Ida L. Lacy and Thomas A. Tennyson, Memphis, Tenn.

Application May 31, 1957, Serial No. 662,705

4 Claims. (Cl. 182—14)

The present invention relates to a traveling scaffold for use in a commercial building.

An object of the present invention is to provide a scaffold which lends itself for support from the overhead structure provided in a commercial building and which includes the mechanism for propelling it backward and forward along said structure.

Another object of the present invention is to provide a scaffold which is adapted to be supported at varying distances from the overhead structure provided in a commercial building.

A further object of the present invention is to provide a scaffold which may be readily assembled and supportingly suspended from the overhead structure provided in a commercial building and which may be detached with facility and ease from such structure and disassembled.

These and other objects and advantages of the present invention will be fully apparent from the following description when taken in connection with the annexed drawings, in which:

Figure 1 is a perspective view of the traveling scaffold of the present invention shown attached to a pair of I-beams for longitudinal travel therealong;

Figure 2 is an end view in elevation of the assembly shown in Figure 1, the dotted line showing illustrating the extensible and contractile movement of the platform and its attached posts showing its adjustment to high beams of varying spacing;

Figure 3 is a view partially in section taken on the line 3—3 of Figure 2, the dotted line shown illustrating the traveling movement of the scaffold in the direction of the arrow;

Figure 4 is a top plan view as seen on line 4—4 of Figure 3;

Figure 5 is a perspective view of the traveling scaffold according to the present invention, showing it in a position lifting itself toward an overhead support;

Figure 6 is a sectional view, on an enlarged scale, taken on line 6—6 of Figure 3;

Figure 7 is a sectional view, on an enlarged scale, taken on line 7—7 of Figure 5;

Figure 8 is a perspective view of a means of attachment to a sub-beam;

Figure 9 is a sectional view, on an enlarged scale, taken on line 9—9 of Figure 8;

Figure 10 is a sectional view, taken on an enlarged scale, taken on the line 10—10 of Figure 8;

Figure 11 is an end elevational view showing the traveling scaffold supported on the sub-beams of Figure 8 and moving between laterally spaced overhead supports;

Figure 12 is an elevational view, on an enlarged scale, taken on line 12—12 of Figure 11; and

Figure 13 is an elevational view, similar to Figure 7, showing the driving connection of the cables to the traveling platform in the condition of use shown in Figure 11.

Referring in greater detail to the drawings in which

like numerals indicate like parts throughout the several views, the traveling scaffold according to the present invention comprises a platform 20 having on one side, at each end thereof, a post 22 having its lower end pivotally connected to the upper end of a side wall 24 which is formed integrally with the platform 20 adjacent the edge thereof.

Each post 22 consists in an outer tubular member 26 and an inner tubular member 28 projecting from the open upper end of the outer member 26 and slidably connected thereto. The nut and bolt assembly 30 is provided for each post 22 for releasably locking the members 26 and 28 together in any adjusted position of extensible and retractile movement.

On the upper end of each of the members 28 is a suspension means including a box frame 32 having a bushing 34 formed integrally therewith for the support of a horizontally disposed drive shaft 36. The drive sprocket 38 is keyed to one end of the shaft 36 and the other end of the shaft 36 has splined to it a drive roller 40. An auxiliary box frame 42 is supported in the box frame 32 and forms a means of support for a horizontally disposed support arm 44 slidably mounted within the frame 42. One end of the arm 44 carries 25 a handle 46 and the other end carries an upright post 48 carrying a rotatable roller 50 on the upper end thereof. The drive roller 40 and the roller 50 are horizontally disposed and are arranged in end-to-end spaced relation. Sliding movement of the support arm 44 relative to the frame 42 shifts the roller 50 toward and away from the roller 40. The rollers 40 and 50 of each post engage opposite sides or flanges of the adjacent I-beam 92, as shown in Figure 6.

An identical post 22' is positioned between the end posts 22 and carries all of the same components heretofore described with the exception of the drive sprocket 38. The posts 22, 22' are arranged in spaced relation along one side of the platform 20 and other posts 52 are arranged along the other side of the platform 20 opposite to the posts 22 with a third post 52' opposite the post 22'. The posts 52, 52' are identical in structure with the posts 22, 22' and carry the same components. The means pivotally connecting each post 22, 22', 52 and 52' to the upper ends of the walls 24, 54 includes a pair of spaced L-shaped brackets 21, each having one leg 23 horizontally disposed and fixedly secured to the upper end of the adjacent wall 24 or 54 and having the other leg 25 vertically disposed. The legs 25 of each pair of brackets 21 are disposed one at each end of a bearing block 27 carried on the lower end of the posts 22, 22', 52 or 52'. A pivot pin 29 extends through the legs 25 of each bracket 21 and through the adjacent bearing block 27, pivotally connecting the adjacent post to the platform 20. In addition to being pivotally connected at their lower ends to the other side wall 54, the posts 52, 52' are also movable as a unit toward and away from the posts 22 and 22'. Means for moving the posts 52, 52' and the associated side wall 54 consists in a hollow beam 56 below the platform 20 and having therein a slidably mounted auxiliary beam 58 as shown in Figures 2 and 3. The beam 58 supports the side wall 54 for sliding movement toward and away from the side wall 24. A rack 60 driven by a gear 62 which is on the end of a shaft 64 journaled beneath the platform 65 20. A drive belt 66 (Figure 1) connects the shaft 64 to a driven pulley 68 mounted on a jack shaft 70 (Figure 7) journaled in pillow boxes 72 (Figure 3) mounted upon the platform 20. An idler pulley 74, controllable by the hand lever 76 is movable into and out of engagement with the belt 66 to cause rotation of the shaft 64 and results in movement of the side wall 54 toward and away from the side wall 24.

Motor means is carried by the platform 20 and consists in an electric motor 78 drivably connecting by a belt 80 the cross shaft 82 to the motor 78 by means of bevel gear assemblies 84 across shaft 78. The cross shaft 82 has a telescoping section 82' slidably therewithin in chain drives 86 and 88 connect a cross shaft 82, 82' to the drive sprockets 38 at the upper ends of the posts 22 and 52.

Rotatable roller means is positioned beneath the platform 20 inwardly of each side of the latter and is drivably connectable to the aforesaid motor means and engageable by cables 90 (Figure 5) for lifting the platform 20 to an elevated position beneath a roof structure constituting a support means such as the I-beams in Figure 5 designated by the reference numeral 92. A loop is formed on one end of the cables 90, designated by the numeral 94, in Figure 5, through which passes a midportion of another of the cables 90 which passes through a port provided in the side walls 24 and 54 and under the rollers 86 and 98, Figures 1 and 5. A double-ended hook 100 mounted on an intermediate portion of the roller 96 provides a means for attachment of one end of the cables 90 as shown in Figure 13. Clutch means is provided between the roller 96 and a drive pulley 102 mounted upon the jack shaft 70 for controlling the take-up of the one cable 90 upon the roller 96. Specifically this clutch means includes an idler pulley 104 controllable by a hand lever 106 and engageable with a belt 108 drivably connected as seen in Figures 1 and 13 to the roller 96.

Referring to Figures 8 to 12, inclusive, means is provided by the present invention for moving the scaffold from one set of I-beams 92 to other I-beams 92. This means includes the provision of sub-beam assemblies designated generally by the reference numeral 110 and including a short length of I-beam 112 the lower flange of which support the rollers 40 and 50 without movement thereon. Hangers 114 support the I-beams 112 and are themselves provided with rollers 116 by means of which they move on an overhead support or other I-beam 92' (Figure 11) between the adjacent I-beams 92 as a result of winding of the cable 90 upon the roller 96. Each of the hangers 114 has to be removed when one of the I-beams 92 is encountered and replaced on the other side of the I-beam 92 as the platform 20 is moved along the longitudinal length of the I-beam 92' to its new position as desired.

In use, the traveling scaffold according to the present invention may be supported on any two adjacent I-beams in a building structure, such as a warehouse or the like, and may be self-propelled the lengths and longitudinally of such I-beams and may be transported through the air from one pair of I-beams laterally to another pair of I-beams. It is only necessary to adjust the width of the platform 20 by the controls which effect the movement of the rack 60 to adjust the posts 22 and 52 to the proper width for the spacing of the particular I-beams 92. Movement laterally of such I-beams 92 is effected by attaching the sub-beam assemblies 110 to the posts 22 and 52 and thereafter attaching the assemblies 110 to the hangers 114 and to thereafter move by means of the cables 90 the scaffold laterally of the I-beams 92 to the desired new position. Each of the posts 22 and 52 may be pivotally swung at its lower end so as to enable it to be moved from one I-beam to another I-beam. This is accomplished by first attaching the cables 90 to an adjacent I-beam 25 that the platform is supported therefrom. Next, the roller 50 on the upper end of the posts 22, 22', 52 or 52' is shifted away from the adjacent drive roller 40. The posts may then be swung about the associated pivot pin 27 to free the roller 40 from engagement with the flange of the I-beam. When all the posts are disconnected from the I-beams, the platform 20 may be shifted laterally on the cables 90 to the new position for attachment to the other I-beams. Wheels 116 are pro-

vided at each corner of the platform 20 for movement of the scaffold upon a supporting surface when not suspended by either of the suspension means including the hangers 114, the cables 90, or the drive rollers 40 on the upper ends of the group of posts carried by the upper ends of each of the side walls 24 and 54.

Special means is provided for quick attachment of the cables 90 to a distant I-beam for pulling of the cables 90 and the winding thereof on the roller 96. This means is shown in Figures 8 to 10, inclusive, and includes pincher-type hangers 118 dependently carrying a box frame 120 which supports a pair of spaced parallel rollers 122 and 144 and vertical rollers 126. The hangers 118 permit the quick attachment of the box frame 120 to any particular I-beam 92 so that the traveling scaffold according to the present invention may be rapidly moved to a new position suspended from any adjacent beams 92 in a building having spaced side walls. The width of the platform 20 may be rapidly adjusted to fit beams 92 of different spacings by extending the rack 60 at each end of the platform 20 to shift the auxiliary beams 58 inwardly or outwardly of the hollow beams 56, the beam 56 constituting a cross member at each end of the platform 20 extending between the adjacent ends of the rigid side walls 24 and 54 and having one end fixed to the side wall 24, the auxiliary beam 58 constituting means connecting the beam 56 at each end of the platform 20 to the adjacent ends of the other side wall 54 for movement of the side wall 54 toward and away from the side wall 24.

What is claimed is:

1. For use in the interior of a building having opposed spaced walls, and a plurality of overhead beams arranged in transverse spaced relation positioned between and supported on said walls, a traveling scaffold comprising a platform having opposed edges adapted to be positioned between and below adjacent beams, a first group of posts arranged in spaced relation along one of said platform edges and having the lower ends pivotally connected to said platform, a second group of posts arranged in spaced relation along the other of said platform edges and having the lower ends pivotally connected to said platform, said second group of posts being connected to said platform for movement as a unit toward and away from said first group of posts, suspension means on the upper ends of the posts of said first group and adapted to engage one of said beams for traveling back and forth movement therealong, suspension means on the upper ends of the posts of said second group and adapted to engage another of said beams for traveling movement back and forth therealong, each of said suspension means including a pair of horizontally disposed rotatable rollers arranged in end-to-end spaced relation, one of said rollers being movable toward and away from the other of said rollers, said pair of rollers being adapted to rollably engage opposite sides of the adjacent beam, and means carried by said platform and operatively connected to the suspension means of each of said first and second groups for effecting the traveling movement of said platform along said adjacent beams.

2. For use in the interior of a building having opposed spaced walls, and a plurality of overhead beams arranged in transverse spaced relation positioned between and supported on said walls, a traveling scaffold comprising a platform having opposed edges adapted to be positioned between and below adjacent beams, a first group of posts arranged in spaced relation along one of said platform edges and having the lower ends pivotally connected to said platform, a second group of posts arranged in spaced relation along the other of said platform edges and having the lower ends pivotally connected to said platform, said second group of posts being connected to said platform for movement as a unit toward and away from said first group of posts, suspension means embodying a roller 75 on the upper ends of the posts of said first group and

adapted to engage one of said beams for traveling back and forth movement therealong, suspension means embodying a roller on the upper ends of the posts of said second group and adapted to engage another of said beams for traveling back and forth movement therealong, each of said suspension means including a pair of horizontally disposed rotatable rollers arranged in end-to-end spaced relation, one of said rollers being movable toward and away from the other of said rollers, said pair of rollers being adapted to rollably engage opposite sides of the adjacent beam, and means carried by said platform and operatively connected to the suspension means of each of said first and second groups for effecting the traveling movement of said platform along said adjacent beams.

3. For use in the interior of a building having opposed spaced walls, and a plurality of overhead beams arranged in transverse spaced relation positioned between and supported on said walls, a traveling scaffold comprising a platform having opposed edges adapted to be positioned between and below adjacent beams, a first group of posts arranged in spaced relation along one of said platform edges and having the lower ends pivotally connected to said platform, a second group of posts arranged in spaced relation along the other of said platform edges and having the lower ends pivotally connected to said platform, said second group of posts being connected to said platform for movement as a unit toward and away from said first group of posts, each of the posts of said first and second groups having a fixed lower portion and an upper portion extensible and retractable with respect to the lower portion, and releasable lock means for holding the upper portion in any of the selected positions of its movement relative to said lower portion, suspension means on the upper ends of the posts of said first group and adapted to engage one of said beams for traveling back and forth movement therealong, suspension on the upper ends of the posts of said second group and adapted to engage another of said beams for traveling back and forth movement therealong, each of said suspension means including a pair of horizontally disposed rotatable rollers arranged in end-to-end spaced relation, one of said rollers being movable toward and away from the other of said rollers, said pair of rollers being adapted to rollably engage opposite sides of the adjacent beam, and means carried by said platform and operatively connected to the suspension means of each of said first and second groups for effecting the traveling movement of said platform along said adjacent beams.

4. For use in the interior of a building having opposed spaced walls, and a plurality of overhead beams arranged in transverse spaced relation positioned between and supported on said walls, a traveling scaffold comprising a platform having opposed edges and adapted to be positioned between and below adjacent beams, a rigid side wall extending along one of said platform side edges and fixed thereto, another rigid side wall extending along the other of said platform side edges, a first group of posts arranged in spaced relation along said first-named rigid side wall and each having the lower end pivotally connected to the upper end of said side wall, a second group of posts arranged in spaced relation along said another rigid side wall and each having the lower end pivotally connected to the upper end of said another side wall, means connecting said another side wall to said platform for movement as a unit toward and away from said first-mentioned rigid wall, suspension means on the upper ends of the posts of said first group and adapted to engage one of said beams for traveling back-and-forth movement therealong, suspension means on the upper ends of the posts of said second group and adapted to engage another of said beams for traveling movement back-and-forth therealong, each of said suspension means including a pair of horizontally disposed rotatable rollers arranged in end-to-end spaced relation, one of said rollers being movable toward and away from the other of said rollers, said pair of rollers being adapted to rollably engage opposite sides of the adjacent beam, and means carried by said platform and operatively connected to the suspension means of each of said first and second groups of posts for effecting the traveling movement of said platform along the adjacent beams.
